[57] CLAIM

The ornamental design for a combined sink and faucet, as shown and described.

DESCRIPTION

FIG. 1 is a perspective view of a combined sink and faucet showing my new design;

FIG. 2 is a top plan view thereof;

FIG. 3 is a cross sectional view taken on line 3—3 of FIG. 2; and

FIG. 4 is a cross sectional view taken on line 4—4 of FIG. 2.

The fragmentary broken line representation of a counter top in FIG. 1 is for purposes of illustration only.
